UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

ELECTRICAL CONNECTING AND SUPPORTING DEVICE.

Application filed March 5, 1920. Serial No. 363,419.

The present applicant, by several applications, set out below, has disclosed and claimed broadly devices for supporting an electrical appliance to a wall or ceiling and connecting it electrically with a source of current by means of curved arms connected operatively, both mechanically and electrically with the appliance. By these several applications it was sought to bring out through the range of modifications disclosed therein, the degree of latitude allowed to one skilled in the art for practising the invention without departing from the principle underlying it. For instance, in some cases, the arms are retained in supporting relation to the wall or ceiling by devices which constitute a positive mechanical lock therefor, while in other cases the arms are retained in place by the action of gravity imposed thereon by the weight of the appliance. Further, it has been brought out clearly that the invention is not to be limited to the position of the center of curvature of the arms with relation to any surfaces associated with the devices, any such necessary relation being determined as a matter of design. The several applications referred to are Ser. Nos. 350,688; 350,689 and 350,690 filed January 10, 1920 and Ser. No. 352,087 filed January 17, 1920. By the present invention the range of equivalent structures is further amplified by a different embodiment of the principle. In this case the supporting and connecting arms instead of being carried by the appliance are independent thereof, but are adapted to be engaged operatively thereby, when in position, the relation of the appliance to the supporting arms being such as to lock these arms in place by what may be termed a combination of mechanical and gravity locking action.

A further object of the invention is to improve generally the details of construction of the receptacle and the arms and their carrying block so as to satisfy the manufacturer's and electrician's requirements of simplicity, cheapness, readiness of installation and assembling and unassembling.

In accordance with the illustrated embodiments there will be emphasized other permissible curvatures of the arms and other satisfactory relationships between

such centers of curvature and proximate surfaces in and about the devices.

The invention will be described in greater detail in connection with the accompanying drawings, in which—

Figure 1 is a view in vertical section through an outlet box showing the appliance in its relation thereto when supported and connected by means of the improved connecting and supporting devices, one of the outer side walls of the fibre receptacle being removed in the interest of clearness.

Figure 2 is a view in horizontal section through the receptacle and block shown in Figure 1 and taken along the planes indicated by the broken lines 2—2 of Figure 1 and looking in the direction of the arrows.

Figure 3 is a view in front elevation of the improved receptacle, the wall plate being removed.

Figure 4 is a view in front elevation of one form of the improved supporting plug.

Figures 5 and 6 are detail views in side elevation and end elevation, respectively, of terminal plates within the fibre receptacle.

Figure 7 is a view in vertical section through an outlet box and bracket with which are associated the improved electrical connecting and supporting devices of somewhat modified form, the section being taken on the plane indicated by the broken lines 7—7 of Figure 8 and looking in the direction of the arrows.

Figure 8 is a view partly in horizontal section and partly in plan of the devices shown in Figure 7, the upper half of the receptacle being removed.

Figure 9 is a view in front elevation of the receptacle, the wall plate being removed.

Figure 10 is a detail view in front elevation of the improved plug.

The present application, while illustrating somewhat modified embodiments of the same invention as is set forth in the copending applications hereinbefore referred to, seeks not only to emphasize the simple and inexpensive character of necessary changes and additions to adapt present installations to the proposed standardized form of connecting and supporting devices for electrical appliances, but also to show the small initial cost involved in manufacturing the special

parts which will be required to standardize the means for connecting and supporting such devices wherever found. As pointed out hereinbefore, the underlying thought is 5 to make furniture of such electrical appliances, including lighting fixtures, and to apply such appliances and fixtures to walls or ceilings with the ease which characterizes the hanging of a picture. In order to fully 10 realize such advantageous standardization of electrical appliances, it becomes a primary desideratum to permit wiring installations as now found and the form of electrical appliances, including fixtures, as now 15 put out, to be adapted to the present standardization and at the same time to minimize to the greatest possible degree the cost of any additional parts for connecting such appliances to such wiring installations and 20 supporting them in position. The present case is thought to illustrate a thoroughly practical commercial embodiment of means for bringing about the desired standardization.

25 It is now common practice to wire up a building with an outlet box, such as *a*, at convenient points in the walls and ceilings and to secure to the bottom of this outlet box a fixture stud, such as is indicated at *b*, for 30 the support of fixtures or appliances. Into such outlet box, as *a*, lead wires *c* from a suitable source of current supply. These outlet boxes, when the necessary mechanical and electrical connections have been made 35 with the appliances, are covered by some slight means, such as by a wall plate, indicated at *d*, although this wall plate, it is to be understood, may or may not be modified to adapt it to the present improvements.

40 The appliance or fixture, indicated as a wall bracket *e*, is such as will be purchased by the user, and the present invention has for its broad objects to provide suitable devices whereby such an appliance may be readily 45 supported in place and connected electrically with the source of current supply *c* without requiring the services of a wiring expert or any special mechanical skill in effecting its support. To this end, the invention 50 is concerned with improved electrical connecting and supporting devices which constitute the new elements of the combination of parts. Such elements are, generally speaking, a receptacle indicated at *f* and a 55 plug indicated in Figure 4 as *g*.

The improved receptacle *f* may comprise a central block *f'* of fibre, porcelain or other suitable insulating material, and two end blocks of fibre *f²*, *f³* secured detachably 60 thereto by means of through bolts *h*. The proximate faces of the block *f'* and its end pieces *f²*, *f³* are recessed to receive a terminal plate *i* of metal in which is stamped or otherwise formed a groove *i'*, preferably of

curved outline for a reason which will later 65 appear. The wall *i³* of the groove *i'* is perpendicular to the plate *i* as is the surface *i⁴* of the outer wall of this groove. To the plate *i* is riveted a second terminal piece *k* which extends across the groove *i'* and 70 carries terminal posts *k'* to which are secured the wires *c*.

One feature of the construction of the fibre receptacle *f*, which may be found to be 75 of practical importance, resides in the rabbeting of the opposite side faces of the central block *f'* so as to receive the flanged ends *i²* of the plate *i* and correspondingly rabbeted portions of the end fiber pieces *f²*, *f³* whereby all of the parts are held positively in fixed relation and, when once assembled, resist all tendency for displacement of any one of the sections of the fibre block or of the plates *i*, *k*.

The end blocks *f²*, *f³* may be formed with 80 openings therein to permit the introduction of the wires *c* and their connection with the binding posts *k'*.

Slots *f⁴* appear in the front face of the receptacle *f*, these slots being in registry 90 with the grooves *i'* to receive the conductor arms as will later appear.

The flush receptacle, as herein described, may be placed within the outlet box *a* and secured therein to the fixture stud *b* in a very 95 simple and convenient manner.

As shown in Figure 2, it is proposed to recess the rear wall of the central block *f'* to receive the fixture stud *b* and on this stud is threaded a spider nut *b'* which may be 100 secured in adjusted position on the fixture stud as by means of a screw *b²*. The nut *b'*, in turn, receives a threaded stud *b³* which passes through the front wall of the central block *f'* and has its head *b⁴* exposed at the 105 front of the receptacle *f*, although this head may rest within a recess on the block *f'* and lie within the plane of the front face thereof. In positioning the receptacle within the outlet box with its front face in any desired 110 relation to the wall, it will be understood that the nut *b'* is threaded on to the fixture stud *b* to any desired extent and finally locked in the desired adjusted position by means of the screw *b²*, whereupon the receptacle is secured firmly to the nut *b'* by 115 means of a stud *b³*. Whenever the position of the receptacle is to be changed with relation to the plane of the wall, it is evident that the nut *b'* can be turned on or off the 120 fixture stud *b* to a greater or less extent.

For convenience, the receptacle *f* may have secured thereon angle pieces *f⁵* to which may be secured the wall plate *d*, but the invention is not concerned with any 125 such detail. The wall plate *d* is intended to constitute a slightly covering for the installation and may take any desired orna-

mental form, it being merely necessary that it shall leave exposed the entering slots f^4 for the arms of the plug.

A suitable form of plug connection is illustrated herein. This plug is very inexpensive to manufacture and easy to wire up to the appliance. It comprises generally complementary pieces of fibre g' , g^2 adapted to be united along a vertical plane, one of the pieces g^2 being recessed to receive the bent-over ends l of curved conductor arms l' . These conductor arms pass through slots formed in the piece g^2 . The bent-over sections l of the conductor arms are adapted to receive binding screws l^2 by means of which the electrical connection between the conductor arm is made with the wires e' of the electrical appliance or fixture e . These wires pass into recessed portions of the plug g through suitable side openings g^3 formed in the fibre pieces g' , g^2 . The bent-over portions l rest between the meeting edges of the fibre pieces g' , g^2 above and below the recesses for the binding screws l^2 , so that a firm and secure bearing surface between the arms and the plug is secured. The pieces g' , g^2 are held together partially by screws m and partially by means of a band n which passes around three sides of the plug and is secured thereto by means of a central stud n' . In the interest of compactness this band n is preferably set in a channeled portion of the pieces g' , g^2 , so as to lie flush with the outer surfaces of the plug. Carried with the band n and preferably formed integral therewith is a vertical hook section n^2 which, it has been found in practice, preferably has one face in substantially the plane of the outer face of the plug and the inner face, indicated at n^3 , beveled for a purpose which will appear. The formation of this hook in its relation to the other parts of the receptacle is not a limitation on the scope of the invention, but the features of design mentioned emphasize the simple and compact character which the improved connecting and supporting devices can be made to assume by proper designing.

The embodiment of the conductor arms l' shown in Figure 1 indicates that the center of curvature of these arms, indicated at o , falls in about the plane of the face plate d when the arms are slid through the slots f^4 into engagement with the grooves i' of the terminal plates i . The center of curvature of the grooves i' is, of course, coincident with the center of curvature of the arms. Stresses on the arms l' will be resisted by the wall i^3 of the groove i' and since this wall is perpendicular to the plate i the plate will resist these stresses longitudinally of it. In like manner the surface i^4 of the outer wall of the groove i^3 will seat on the insulating material of the receptacle and place

it under compression. It is to be understood that in some constructions the grooves i' , as such, may not be employed since the curved conductor arms may engage with other forms of abutments which will serve to neutralize the turning moments impressed on the arms and hold them in locked position. Further, it is to be understood that the position of the center of curvature o with relation to the plane of the wall and to the arms is a matter of design that can be changed by those skilled in the art without departing from the invention provided the relation of parts is such as to permit the arms l' to be moved in and out of the slots f^4 .

In the construction shown it is contemplated that the plug g shall be mechanically independent of the appliance (such as a wall bracket e) which is to be supported. However, it is further contemplated that the appliance itself will be so engaged with the plug g when the appliance is in place that the arms l' of the plug will be locked within the receptacle so as to prevent accidental disengagement therefrom. To this end the appliance e has secured to the reverse face of its base a bridge e^2 which is adapted to be slipped into engagement with the beveled face n^3 of the hook n^2 when the plug g is in place. The so-called base of the fixture, whether integral therewith or secured thereto, serves as a canopy to cover the plug and when this canopy is in proper relation to the plug member and fixture it precludes the withdrawal of the plug terminals l' from the receptacle. To remove the appliance e it is raised bodily in a generally vertical plane, thereby disengaging the bridge e^2 from the hook n^2 and then removed from the wall for a sufficient distance to permit withdrawal of the curved arms l' by a generally upward rotative movement of the plug g . When the appliance e is in supported relation to the plug, as shown in Figure 1, the weight of the appliance is transmitted to the plug through the hook n^2 . Further the relation of the bridge e^2 to the hook n^2 is such as to impress a firm binding stress on the curved arms within the receptacle so as to lock them snugly in place. The imposition of any additional stresses on the appliance e , except a direct upward movement thereof, merely increases this locking action. It is evident that the appliance cannot rotate either upwardly or downwardly when in position since its base falls outside of the center of curvature o of the curved arms l' .

The details of construction of the receptacle and plug in the embodiment illustrated in Figures 7-10 are somewhat different from those hereinbefore described. In this embodiment the flush receptacle is made up of two fibre pieces p , p' joined along their hori-

zontal mid plane and formed with registering recesses which, when the blocks are secured together, as by means of through bolts p^2 , form uninterrupted curved grooves in 5 which are supported terminals p^3, p^4 . These terminals may be formed conveniently of reversely bent, metallic pieces, the bases of which receive binding screws q, q' , for engagement with the conductor wires C. The 10 lower plug p as shown in Figure 8 may be recessed, as at p^5 to receive the wires and binding screws and, when the upper plug p' is removed, affords a convenient means of assembling the terminals p^3, p^4 within the 15 block and completing the electrical connections therewith. The curved grooves formed within the receptacle, as described, terminate in slots p^6 in the face of the receptacle to receive entering conductor arms 20 as will appear later. The receptacle may be supported adjustably within the outlet box A by means of a fixture stud B, adjustable nut B' , set screw B^2 stud B^3 and stud head B^4 , all arranged and co-operating in the 25 manner described in greater detail in connection with Figure 2.

The plug shown in Figure 10 differs in details of construction from that shown in Figure 4. It comprises upper and lower 30 halves r, r' , adapted to be held together by a band s which passes around three sides thereof and is secured thereto by means of a through bolt s' . The blocks r, r' are recessed internally to receive enlarged ends t 35 of curved conductor arms t' . The ends t of the conductor arms are engaged by binding screws t^2 for attachment to conductor wires E' of the electrical appliance E. The complementary blocks r, r' may be rabbeted 40 at their corners, as indicated at r^2 , to provide for snug engagement therebetween and prevent relative displacement thereof when the parts are assembled. The retaining band s which encircles the blocks r, r' carries, 45 preferably integral therewith, an upwardly hook s^2 , the inner edge of which is beveled, as at s^3 , for sliding engagement by a transverse bridge E^2 secured to the base E of the electrical appliance. The inner 50 beveled face of the hook s^2 is cut out to afford clearance for the head of the bolt s' , the cut-out portion being indicated by dotted lines at s^5 in Figure 10.

In the embodiment under consideration 55 the conductor arms t' have been shown as having a center of curvature, as at O, which, when the arms are in place, falls within the plane of the face of the receptacle. In such a case, where curved grooves are formed 60 within the receptacle pieces p, p' to receive the arms t' , the center of curvature of such grooves will coincide with the center of curvature of the arms. It is to be understood, however, that grooves in the receptacle are not essential since other abutting

pieces for the arms will serve to equalize the turning moments impressed thereon when in place.

The manner of assembling the parts described is the same as that hereinbefore described. The characteristic features of the devices herein are simplicity, compactness, cheapness of cost and facility of installation and application. If it be assumed that a building were wired up as at present ceiling 75 outlet boxes such as a A with the leading in wires C and usually a fixture stud b B would be found. In such case the rest of the attachments now found will be removed and the improved receptacle indicated at f and 80 that formed by the two pieces p, p' would be secured in place. Once in place no further mechanical or electrical adjustments for the application of the electrical appliance would ever be required. To co-operate with 85 such a receptacle there would be provided with the appliances sold a supporting and connecting plug, such as is indicated at g and is formed by the blocks r, r' . Such a plug when connected to the wires of the 90 appliance could be inserted in any receptacle 95 wherever found and the appliance engaged with the hook n^2, s^2 thereof and thereby lock the conductor arms in supporting engagement with the receptacle.

I claim as my invention:

1. In combination with a fixture, an electrical connecting and supporting device therefor, including a wall receptacle formed with entrance openings and provided with terminals, and a plug member including two upwardly curved conducting and supporting members to engage the terminals and insulating means therefor, and means intermediate the fixture and plug member for supporting the former and positively holding the latter against withdrawal from the receptacle.

2. In combination with a fixture, an electrical connecting and supporting device therefor, including a receptacle formed with entrance openings and provided with terminals, a plug member including a lug, two curved conducting and supporting members to engage the terminals, and insulating means therefor, and means, intermediate the fixture and plug member, co-operating with said lug to support the fixture and positively hold the plug member against withdrawal from the receptacle.

3. An electrical connecting and supporting device including a receptacle formed with an entrance opening and provided with a terminal, and a plug member including fixture supporting means, a curved conducting and supporting member to engage the terminal, and insulating means between the fixture supporting means and said conducting member, said terminal being formed with a bearing surface for the side of the conducting 125 130 135 140 145 150 155 160 165 170 175 180 185 190 195 200 205 210 215 220 225 230 235 240 245 250 255 260 265 270 275 280 285 290 295 300 305 310 315 320 325 330 335 340 and supporting member nearest to the plug member, said receptacle and plug member also including co-operating means for resisting the turning moment of the conducting and supporting member about the said bearing surface in the terminal by the weight of a fixture on the fixture supporting means.

4. An electrical connecting and supporting device including a wall receptacle formed 10 with entrance openings and provided with terminals, and a plug member including fixture supporting means, two upwardly curved conducting and supporting members to engage the terminals, and insulating means between the fixture supporting means and said conducting members, said terminals being formed with curved grooves for the sides of the conducting and supporting members nearest to the plug member, said receptacle 20 and plug member also including co-operating means for resisting the turning moments of the conducting and supporting members about the said grooves in the terminals by the weight of a fixture on the fixture supporting means.

5. A receptacle for an electrical connecting and supporting device formed with entrance openings for curved conducting and supporting members of a fixture supporting plug 30 member of the device, and provided with terminals to be engaged by the conducting and supporting members, said terminals being formed with curved grooves for the sides of the conducting and supporting members 35 nearest to the plug member, said grooves being in such relation to the conducting and supporting members that the weight of a fixture on the fixture supporting means maintains the plug member in operating relation 40 to the receptacle.

6. A plug for an electrical connecting and supporting device including curved conducting and supporting members having inner ends falling without the planes of said members, respectively, insulating blocks having recesses to receive the said inner ends of said members, a strap embracing the blocks and clamping said inner ends between them, and means to hold the parts in fixed relation.

50 7. A plug for a wall electrical connecting and supporting device including two upwardly curved conducting and supporting members, insulating blocks having recesses to receive the inner ends of the members, a strap embracing the blocks and carrying a fixture supporting member, and means to hold the parts in fixed relation.

60 8. A plug for a wall electrical connecting and supporting device including two upwardly curved conducting and supporting members, two insulating blocks having recesses to receive the inner ends of said members, the members passing through one of said blocks, a strap embracing the blocks 65 when joined, a lug on the strap to engage

a fixture, and means passing through the strap and blocks to hold the parts in fixed relation.

9. A plug for a wall electrical connecting and supporting device including two upwardly curved conducting and supporting members, insulating means carried thereby, and a lug on the insulating means to engage a fixture.

10. A stamped plate for a receptacle 75 formed with bearing surfaces, perpendicular to the plate, for a conducting and supporting member of a fixture supporting plug, and with other bearing surfaces perpendicular to the plate for supporting engagement with an insulating portion of the receptacle.

11. A receptacle for an electrical connecting and supporting device including an electrical terminal plate formed with bearing 85 surfaces perpendicular to the plate for a conducting and supporting member of a fixture supporting plug, said plate and the insulating portion of the receptacle having co-operating bearing surfaces perpendicular 90 to the plate for supporting it in the receptacle.

12. A receptacle for an electrical connecting and supporting device including terminal plates formed with grooves having bearing surfaces perpendicular to the plate for curved conducting and supporting members of a fixture supporting plug, said plate and the insulating portion of the receptacle being formed with co-operating bearing surfaces perpendicular to the plate for the support of the plate in the receptacle.

13. An electrical connecting and supporting device for a fixture including in combination, a receptacle formed with entrance 105 openings and provided with terminals, a plug member independent of the fixture and having terminals connected electrically with the fixture and engageable with the terminals within the receptacle, means intermediate the fixture and plug member and insulated from said terminals to support the fixture detachably on the plug member, and means to preclude the withdrawal of said plug terminals from said receptacle when 110 the fixture is in supported relation to the plug.

14. An electrical connecting and supporting device for a fixture including in combination, a receptacle formed with entrance 120 openings and provided with terminals, a plug member covered by the base of the fixture and having terminals connected electrically with the fixture and engageable with the terminals within the receptacle, and means intermediate the fixture and plug member and insulated from said terminals to support the fixture detachably on the plug member, the base of said fixture normally precluding withdrawal of said plug 125 130 135

terminals from said receptacle when the fixture is in supported relation to the receptacle.

15. An electrical connecting and supporting device for a fixture having a bridge element including in combination, a wall receptacle formed with entrance openings and provided with terminals, a plug member having terminals connected electrically with the fixture and engageable with the terminals within the receptacle, and a vertical lug carried with the plug member and insulated from said terminals and adapted to be engaged detachably by said bridge element to support the fixture.

16. An electrical connecting and support-

ing device for a fixture having a bridge element including in combination, a wall receptacle formed with entrance openings and provided with terminals, a plug member having terminals connected electrically with the fixture and engageable with the terminals within the receptacle, and a vertical lug formed with a beveled inner face carried with the plug member and insulated from said terminals and adapted to be engaged detachably by said bridge element to support the fixture. 20 25

This specification signed this 25th day of February, A. D. 1920.

ERNEST CANTELO WHITE.
